Attorneys.

UNITED STATES PATENT OFFICE.

JOHN C. SWAN, OF MARIETTA, OHIO.

METHOD OF EXCLUDING WATER FROM DRILLED WELLS FOR OIL.

1,307,027.

Specification of Letters Patent. Patented June 17, 1919.

Application filed September 7, 1918. Serial No. 253,082.

To all whom it may concern:

Be it known that I, JOHN C. SWAN, a citizen of the United States, residing at Marietta, in the county of Washington and

5 State of Ohio, have invented certain new and useful Improvements in Methods of Excluding Water from Drilled Wells for Oil, of which the following is a specification.

In the usual methods of drilling wells for 10 oil, it is the custom when a water-bearing stratum is encountered and drilled through to insert into the bore, a casing consisting of a series of lengths of connected steel or iron pipes of suitable diameter, this casing 15 extending beneath the water-bearing stratum and thereby shutting off the water from the bore. As successive water bearing strata are encountered, additional strings of casing are inserted. These successive strings 20 extend one inside the other from the surface to a location below the water and the need of them necessitates the starting of the bore with a sufficient diameter to permit the insertion of as many strings of casing as may 25 be necessary.

Obviously, large quantities of steel and iron in the form of pipes, are used, and the cost of transportation to the location where the hole is being bored and the cost of labor 30 for their installation is very large in addition to the purchase cost.

Further the drilling of an initially large hole is necessitated, which adds to the cost of the well.

35 It is the object of my invention to obviate the necessity for using successive strings of casing and the necessity and expense of large hole drilling and these objects I attain by sealing up the successive 40 water bearing strata in the bore by the method which will now be described.

My method consists in first preferably 45 heating the porous, seamed, or stratified rock through which the water enters the bore, to such a degree that a fluid sealing compound forced into the bore, will freely enter the pores or interstices of the water-containing stratum and will thereafter congeal or set into a mass sufficiently solid to 50 prevent the further ingress of water into the bore. As such sealing compounds I prefer to use materials which are liquid at temperatures above the natural temperature of the water bearing stratum, but which will be 55 solid or semi-solid at that temperature. Such materials are paraffin, resin, coal-tar,

pitch, asphalt, etc., either alone or in suitable combination with each other or other materials which will give them the property above referred to.

In carrying out my method, where a compound is used which requires heat to make it liquid, I force into the well a suitable heating medium such as hot water which may be heated under sufficient pressure to raise its 60 temperature to a suitable degree above its boiling point at atmospheric pressure. The hot water is forced into the well under sufficient pressure to overcome the hydrostatic head of the water in the porous stratum 65 and forces its way into the porous mass thereby heating the same to such a degree that when the liquefied sealing compound is introduced it will be able to permeate the water bearing strata to the desired extent to 70 insure complete exclusion of the water from the bore of the well when the material is allowed to cool and set in place.

Different filling materials will require different temperatures for successful penetration of the porous rock, e. g. asphalt will require a considerably higher temperature than paraffin.

These operations may be carried out by any suitable form of apparatus, one form being shown in the accompanying drawing, in which—

Figure 1 is a section through a drilled well with my apparatus in place; and

Fig. 2 is a continuation of the apparatus 90 shown in Fig. 1.

Referring to these drawings, 1 is the bore of the well. 2 is a string of steel or iron pipes extending downward into the bore. Surrounding the string 2 is a second string 95 3 whose lower length is, at its lower end, secured through suitable couplings 4 to the pipe 2. As shown, this connection is made by an ordinary form of screw pipe coupling, but it is preferred to weld this joint so that 100 the lower portion of the pipe 3 is hermetically sealed to the interior piping 2. At its upper portion the pipe 3 is provided with a stuffing box 5 through which passes the pipe 2, and is also provided with a T-head 105 to which is connected the pipe 6 provided with an outwardly opening check valve 7, and a shut-off valve 8, this pipe leading, as indicated to any suitable form of vacuum pump. The purpose of this arrangement is 110 to provide around the greater portion of the length of the pipe 2 a heat insulating cham-

ber whereby the loss of heat from the hot water and rock filling compound is prevented.

While I have described means for producing a substantial vacuum, this may be unnecessary at depths of less than 1000 feet, and the dead air space alone will probably afford sufficient heat insulation to maintain a workable temperature for both the hot water and the hot liquid filling material passed down the pipes 2.

It will be understood that the strings of pipe 2 and 3 are made up concurrently before being lowered into the well so that none of the water present in the well can find its way into the space between the string 2 and the string 3, and it is essential that water shall be excluded from this space.

As shown in Fig. 2 the upper portion of the pipe 2 is provided with a coupling 40, to which is connected a valved pipe 20 leading to a suitable source of pressure fluid such as cold water, gas or air. Another valved pipe 42, is connected to any suitable means for supplying hot water, such as a steam boiler, not shown. A removable screw-plug 16 is located at the top of the coupling to permit the insertion of the expansible pistons 17 and 18. These pistons are preferably cylinders of rubber formed with a central cavity.

Below the end of the heat insulating casing 3 and around the pipe 2 and between that pipe and the wall of the bore is inserted an oil well packer 9 of the construction commonly used in oil wells, or of any special construction which the special circumstances of use may require. As shown the packer consists of a rubber tube 10 compressed between flange couplings 11 and 12, the coupling 11 being secured to the pipe 2, and the coupling 12 resting upon an extension 13 of the packer body which is in turn screwed into the perforated pipe 14, this pipe constituting in effect a continuation of the pipe 2. As will be readily understood this packer provides a slip joint for the pipe 2 whereby the weight of the superincumbent strings of pipe will compress the rubber and force it inwardly and outwardly into a water tight engagement with the pipe 2 and the walls of the bore. The perforated pipe 14 is provided at the bottom with a screw cap closure 15.

The upper portion of the pipe 2 is machine-finished on the outside to provide a smooth surface whereby the pipe under the expansion incident to heat may pass freely through the stuffing box 5 while maintaining a hermetically sealed joint.

In operation the vacuum pump withdraws the air from the space between the pipes 2 and 3 thereby forming an effective heat insulation around the pipe 2. Hot water which has been heated preferably under

pressure so that it is at a suitable temperature, is passed downwardly from pipe 42 through the pipe 2 and out through the perforations in the pipe 14 and thence into the chamber formed between the packer and the bottom of the well, and flows into the pores, crevices or seams of the water-bearing porous rock, forcing back the water contained therein, and in its passage heating the body of the rock to a suitable temperature. This flow of hot water is continued for a time, which will depend upon the character of the rock, until the heating to the requisite temperature has extended radially from the bore to a sufficient distance. The supply of hot water is then shut off, the plug 16 at the top of pipe 2 is removed and an expansible piston 17, preferably of rubber, is then inserted into the pipe 2 and the charge of liquid filling compound is introduced. A second expansible piston 18 is then inserted over the charge of liquid filling compound and the plug 16 replaced. The pistons are then forced down into the bore by a suitable pressure means, such as cold water or high pressure air or gas introduced through the pipe 20. Under the pressure thus exerted the lower piston will move to the bottom of pipe 2 whereupon the charge of liquid filling compound will flow through the perforations and into the interstices, seams or crevices in the water bearing porous rock. This impregnation of the water bearing stratum will proceed from the bore outwardly until the liquid filling material comes into contact with the rock material at a temperature low enough to cause it to congeal or freeze in place thereby completely sealing the orifices through which water enters the seal and the balance of the filler is held under pressure for the necessary period of time to effect cooling to congelation.

This same operation is repeated as often as water producing strata are penetrated by the bore. In the absence of caving walls the bore of the well may be of the same diameter from the surface of the ground to the finished depth of the well.

After the withdrawal of the strings of pipe 2 and 3 and the packing, the residual mass of filling material can be drilled up by the usual process of drilling.

It will be apparent therefore that my invention enables a perfectly and permanently dry well to be bored without the use of any casings for the purpose of excluding water, since the filling material when solidified forms a water-excluding barrier of sufficient strength to withstand the hydrostatic pressure behind it.

Ordinarily water is encountered in sandstone which varies in texture from large crystalline formation to very fine grain.

It will be readily understood that the coarser grained structure will absorb larger

quantities of the filling material and fill 5
farther back from the bore hole than the
finer grain formation; and in the event of
large crevices being present, a larger quan-
tity of filling material must be used to ob-
tain the necessary penetration for successful
water exclusion.

While I have above referred to certain
materials as suitable for use as filling
10 materials it is to be understood that any other
material which is not soluble in or miscible
with water and possessing the physical
properties heretofore described may be used
in lieu of the specifically mentioned
15 materials.

I claim:—

1. The method of preventing the flow of
water from a water-bearing stratum into a
drilled well without casing through the
20 water-bearing stratum which consists in filling
the interstices and crevices of such stratum
by forcing thereinto a hot liquid ma-
terial, insoluble in water, but capable of
solidifying, when cooled to the natural tem-
perature of such stratum, to form a seal
against the further entrance of water.

2. The process as claimed in claim 1, in
which the rock-substance in the water-bearing
stratum is heated before the introduc-
tion of the hot filling material. 30

3. The process as claimed in claim 2 in
which the heating is effected by highly
heated water.

4. The method of preventing the flow of
water from a water-bearing stratum into a 35
drilled well without casing through the
water-bearing stratum which consists in filling
the interstices and crevices of such
stratum by forcing thereinto a hot liquid
material, insoluble in water, but capable of 40
solidifying, when cooled to the natural tem-
perature of such stratum, to form a seal
against the further entrance of water and
maintaining the pressure on the filling ma-
terial for the necessary period of time to ef- 45
fect cooling thereof to solidification.

In testimony whereof, I affix my signature.
JOHN C. SWAN.
